UNITED STATES PATENT OFFICE.

IRA K. JOHNSON, OF CALDWELL, NEW JERSEY, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

Application filed August 23, 1920. Serial No. 405,366.

To all whom it may concern:

Be it known that I, IRA K. JOHNSON, a citizen of the United States, residing at Caldwell, in the county of Essex and State 5 of New Jersey, have invented certain new and useful Improvements in Railway Signaling, of which the following is a specification.

My invention relates to railway signaling, 10 and particularly to signaling of the type wherein roadside signals are controlled by track circuits each comprising a source of current and a track relay. The invention is especially well adapted for, though not limited 15 to, systems of this type wherein the track relays are polarized, and means are provided for reversing the polarity of the current supplied to the track rails by such sources.

Broadly stated, my invention consists in 20 the provision of an auxiliary source of current which is normally disconnected from the track circuit, and means for connecting such auxiliary source with the track circuit at such times as additional voltage on the 25 track circuit may be desirable, such, for example as when the polarity of the track circuit current is being reversed in the instance of the polarized system referred to above.

I will describe one form of railway signaling system embodying my invention and will then point out the novel features thereof in claims.

The accompanying drawing is a diagrammatic view showing one form of signaling system embodying my invention.

Referring to the drawing, the reference characters 1 and 1^a designate the track rails of a railway along which traffic normally moves in the direction indicated by the arrow. These rails are divided by insulated joints 2 to form a plurality of block sections, of which only two sections A—B and B—C are shown in the drawing.

Located adjacent the entrance end of each section is a railway signal which is designated by the reference character S, with an exponent corresponding to the location. Each signal, as here shown, is of the semaphore type, comprising two arms 3 and 4, the former being known as the "home" arm,

and the latter as the "distant" arm. As is well understood each signal indicates "proceed" when both arms are in inclined positions, "caution" when the home arm 3 is inclined and the distant arm 4 is horizontal, 55 and "stop" when both arms are in the horizontal positions. It is understood that this type of signal is chosen only for purposes of illustration, and that any other type of signal may be employed without departing 60 from the scope of my invention.

Each block section is provided with a track circuit comprising a main source of current connected across the rails at the exit end of the section and a track relay connected across the rails at the entrance end. The main source of current for each track circuit is designated by the reference character D with an exponent corresponding to the location, and as here shown this source 70 of current comprises two cells of battery connected in multiple. Interposed between the track battery D and the track rails is a pole-changer designated by the reference character P with an exponent corresponding 75 to the location, which pole-changer is operated by the arm 3 of the signal for the section next in advance. Each track relay is designated by the reference character T with a suitable exponent, and as here shown is of 80 the polarized type, comprising neutral armature contacts 6 and 10, and a polarized armature contact 13, the latter contact being closed only when the relay is energized by what I will term current of normal polarity. 85

Each signal S is controlled by the track relay T for the corresponding section, and for this purpose each signal is provided with a caution circuit and a proceed circuit. Considering signal S^c, for example, the caution circuit is from battery F^c, through wire 5, neutral contact 6 of track relay T^c, wires 7 and 8, operating mechanism for home arm 3 of signal S^c, wire 9, neutral contact 10 and wire 11 to battery F^c. This circuit is, of 90 course, closed when track relay T^c is energized in either direction. The proceed circuit for signal S^c is from battery F^c, through wire 5, contact 6, wires 7 and 12, polar contact 13, wire 14, operating mechanism for 95 100

distant arm 4, wire 9, contact 10 and wire 11 to battery F^c . This circuit is, of course, closed only when relay T^c is energized by current of normal polarity.

The apparatus thus far referred to is well known in the art, and its operation will be understood without detailed explanation. As shown in the drawing, the section immediately to the left of location A is occupied 10 by a car or train, represented by a pair of wheels and an axle W, so that track relay T^a is open and signal S^a indicates stop. Pole-changer P^a is, consequently, in such position that current of reverse polarity is supplied to track relay T^b so that signal S^b indicates 15 caution. The home arm 3 of signal S^b being in the inclined position, pole-changer P^b is in such position that current of normal polarity is supplied to track relay T^c , so that signal S^c indicates proceed. When the car or train W passes out of the section to the left of point A, track relay T^a will become 20 energized in reverse direction, so that home arm 3 of signal S^a will move to the inclined position, thereby shifting pole-changer P^a . Current of normal polarity will then be supplied to track relay T^b , so that signal S^b will indicate proceed.

In systems of the character thus far described, it is well understood that when a pole-changer is reversed, due to the movement of a signal from stop to caution position, the neutral contacts of the track relay controlled by such pole-changer will open 30 momentarily, thereby momentarily opening the caution indication circuit for the signal controlled by such relay. When signals of certain types are used, this momentary opening of the caution indication circuit will permit the home arm 3 of the signal to move to the horizontal position, this action being commonly known as the tripping of 40 the signal. To avoid such tripping it has been customary to provide slow-acting means to prevent the release of the signal during the momentary opening of the caution indication circuit. This has been accomplished by the provision of a slow-acting relay interposed between the track relay and 50 the signal, and it has also been accomplished by the use of a slow-acting magnet to hold the signal in the caution position.

One object of my invention is the provision of means for increasing the voltage applied to a track circuit at the time that the pole-changer in such track circuit is reversed, thereby reducing to a minimum the interval of time during which the neutral contacts of the track relay are open, thereby 60 avoiding the necessity for the slow-acting means referred to above, or at least reducing to a minimum the time-element required in such slow-acting means. As here shown, I accomplish this by means of an auxiliary battery at each signal location, which bat-

tery is designated by the reference character X with a suitable exponent. Each of these batteries is normally disconnected from the track circuit, but is included in the track circuit in multiple with battery D while the pole-changer P is reversing. This is accomplished by means of a circuit controller E operated by the home arm 3 of the adjacent signal. Each circuit controller E is open 70 when the signal indicates proceed, caution and stop, but is closed just before pole-changer P operates, remains closed during the operation of the pole-changer, and is opened after the operation of the pole-changer is completed. 75

I have found that by virtue of this construction I am able to eliminate the slow-acting means, and that the signal will not trip during the reversal of the pole-changer because of the extremely short interval of 80 time during which the neutral contacts 6 and 10 of the track relay are open.

One important advantage of my invention is, of course, the elimination of the necessity for slow-acting holding magnets and slow-acting relays. Another important advantage lies in the economy of battery consumption. The main battery D need be only of sufficient voltage to insure that the track relay T will close after a train passes 90 out of the section. This reduction of voltage and consequent reduction of the current flowing in the track rails adds materially to the safety factor of the track circuit; that is, the shunting effect of trains, light engines, cabooses, and of switch boxes is maximum. Furthermore, the reduction of voltage to the minimum reduces to the minimum the possibility of the flow of current from one section to the next through defective insulated joints. The energy delivered by the auxiliary batteries X is extremely small, owing to the fact that these batteries are in use only when a home signal arm 3 is moving between the inclined and the horizontal position, and so it follows that the life of 100 these batteries is extremely long. 105

Although I have herein shown and described only one form of railway signaling system embodying my invention, it is understood that various changes and modifications may be made therein within the scope of the appended claims without departing from the spirit and scope of my invention. 115

Having thus described my invention, what I claim is:

1. A railway signaling system comprising a plurality of successive block sections, track circuits for the sections each including a main source of current and a polarized relay, signals for the sections controlled by said relays, and means controlled by each signal for reversing the polarity of the current supplied to the rails of the section in the rear; characterized by the combination 120

therewith of an auxiliary source of current for each block section normally disconnected from the rails of the section, and means controlled by each signal for connecting the 5 auxiliary source of current for the section in the rear with the rails of the section at the time that the polarity of the current supplied to such section is being reversed.

2. A railway signaling system comprising 10 a plurality of successive block sections, a track circuit for each section including a main source of current and a polarized track relay, a signal for each section controlled by the relay for the section, and a pole- 15 changer for each track circuit interposed between the source of current and the track rails and operated by the signal for the section next in advance; characterized by the combination therewith of an auxiliary 20 source of current for each track circuit normally disconnected from the track circuit, and means controlled by each signal for connecting the auxiliary source of current for the section in the rear in multiple with the 25 main source for such section at the time that the pole-changer for such section is operated.

3. A railway signaling system comprising 30 a plurality of successive block sections, a track circuit for each section comprising a main source of current and a track relay operated by current from said source, signals for the sections controlled by said relays, an auxiliary source of current for each section for assisting said main source in the operation 35 of said track relay and normally disconnected from the track circuit for the section, and means for each section for at times including said auxiliary source of current in the track circuit for the section.

4. A railway signaling system comprising 40 a plurality of successive block sections, a track circuit for each section comprising a main source of current and a track relay, signals for the sections controlled by said relays, an auxiliary source of current for each section normally disconnected from the track circuit for the section, and means controlled by the signal for each section for at times including the auxiliary source of current 45 in the track circuit for the section in the rear.

5. A railway signaling system comprising 50 a plurality of successive block sections, a track circuit for each section comprising a main source of current and a track relay operated by current from said source, signals for the sections controlled by said relays, an auxiliary source of current for each section for assisting said main source 55 in the operation of said track relay and normally disconnected from the track circuit for the section, and means for each section for at times connecting said auxiliary source of current in multiple with the main source 60 for such section.

6. In combination, a section of railway track, a main battery constantly connected across the rails of the section and an auxiliary battery normally disconnected from said rails, a track relay connected with the 70 rails of said section, and means for at times connecting said auxiliary battery across the rails of said section.

7. In combination, a section of railway track, a main battery constantly connected 75 across the rails of the section and an auxiliary battery normally disconnected from said rails, a polarized track relay connected with the rails of said section, a pole-changer interposed between said main battery and the track rails, means for connecting said auxiliary battery in multiple with said main battery just before said pole-changer is shifted and for opening such connection after the pole-changer has been shifted, and 80 a signal controlled by said relay.

8. In combination, a section of railway track, a main battery constantly connected 85 across the rails of the section and an auxiliary battery normally disconnected from 90 said rails, a polarized track relay connected with the rails of said section, a pole-changer interposed between said main battery and the track rails, means for connecting said auxiliary battery in multiple with said main 95 battery when said pole-changer is operated, and a signal controlled by said relay.

9. In combination, a track circuit including a source of current and a polarized relay, means for reversing the polarity of the 100 current supplied to said track circuit by said source, means for increasing the voltage applied to said track circuit when said reversing means is operated, and a signal controlled by said relay.

10. A railway signaling system comprising 105 a plurality of successive block sections, a track circuit for each section including a source of current and a polarized relay, a signal for each section controlled by the corresponding relay and arranged to indicate proceed or caution according as the relay is energized in normal or reverse direction, a pole-changer for each track circuit interposed between the source of current and the track rails 110 and operated by the signal for the section next in advance, and means for each section for increasing the voltage applied to the track rails thereof at the time of the reversal of the corresponding pole-changer. 115

11. In combination, a section of railway track, a main source of current constantly connected with the rails of said section, a pole changer interposed between said source and said rails, a track relay connected with 120 the rails and responsive to reversals of said pole changer, an auxiliary source of current normally disconnected from said rails, and means for connecting said auxiliary source of current with the rails just before said 125 130

pole changer is shifted and for disconnecting the auxiliary source from the rails after the pole changer has been shifted.

12. In combination, a section of railway track, a main source of current constantly connected with the rails of said section, a pole changer interposed between said source and said rails, a track relay connected with the rails and responsive to reversals of said

10
pole changer, an auxiliary source of current normally disconnected from said rails, and means for connecting said auxiliary source of current with the rails of said section when said pole changer is operated.

In testimony whereof I affix my signature.

IRA K. JOHNSON.
